CLAIM

The ornamental design for an acetabular cup liner, as shown and described.

DESCRIPTION

FIG. 1 is a front perspective view of a first embodiment of an acetabular cup liner;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof; and

FIG. 7 is a bottom plan view thereof.

FIG. 8 is a front perspective view of a second embodiment of an acetabular cup liner;

FIG. 9 is a front elevational view thereof;

FIG. 10 is a top plan view thereof;

FIG. 11 is a rear side elevational view thereof;

FIG. 12 is a first side elevational view thereof, the other side being identical with this view;

FIG. 13 is a bottom plan view thereof; and,

FIG. 14 is a bottom plan view thereof.

Portions of the figures enclosed in broken lines form no part of the claimed design.
